UNITED STATES PATENT OFFICE.

CARL G. KOPPITZ, OF GREENSBURG, PENNSYLVANIA, ASSIGNOR TO RAILWAY AND INDUSTRIAL ENGINEERING COMPANY, OF GREENSBURG, PENNSYLVANIA, A CORPORATION OF PENNSYLVANIA.

PROCESS OF AND APPARATUS FOR MAKING ARTICLES OF CERAMIC MATERIAL.

Application filed May 25, 1923. Serial No. 641,490.

This invention relates to process of and apparatus for making articles of ceramic material and more particularly to the manufacture of high-voltage insulators.

5 Practically all high-voltage insulators as made at the present time consist of a number of units in end to end relation, the number of units depending upon the voltage of the line to be insulated. In the case of 10 pintype insulators a plurality of shells are cemented together with the usually grounded pin on the inside and the line and the wire on the top and the outside. In the case of suspension insulators and post-type 15 insulators each of the separate units making up the complete insulator is provided with inside and outside hardware, the latter serving to secure the units in end to end relation as well as providing at one end a support 20 for the insulator as a whole and affording at the other end an attachment of the current carrying conductor.

As is well recognized by experts, standard insulators of the type referred to, particularly those used on higher commercial voltages, say 44000 and above, have inherently certain drawbacks, the more important ones of which are as follows:

30 1. They are made up of many separate pieces of porcelain or other ceramic material.

2. In the case of suspension and post-type insulators each separate unit requires two pieces of hardware.

35 3. The insulating material is stressed electrically to a high limit between the pieces of hardware.

40 4. Owing to the high electrical stress on the porcelain failure frequently occurs due to certain weathering and aging conditions, which means a short life and high replacement cost.

45 5. The distribution of electrical stress between the different units of an insulator is very uneven due to the inequality of the charging current carried by the different units, which results in a high voltage drop across the unit next to the conductor and a comparatively low voltage drop across 50 the unit next to the grounded support with

correspondingly graded variations on the intermediate units.

6. In the case of electrical flash-over of the insulators of the suspension and post-type in service the resulting power arc is 55 very likely to be held in close contact with the porcelain due to the action of the intermediate pieces of hardware, which often results in a shattering of the porcelain by the intense heat of the arc.

60 From points 1 and 2 it is evident that the cost of manufacture is relatively high while points 3-6 indicate a high cost of replacement.

65 The practice of employing insulators composed of a number of units in end to end relation and having the disadvantages pointed out instead of using insulators composed of a relatively small number of units or of a single unit of uniform character from end to end, is probably due to the fact that the cost of manufacture of the latter by the old methods or processes was so high as to inhibit the general use 70 thereof.

75 It is the general object of the invention to provide a process of and apparatus for cheaply making articles of ceramic material.

80 It is a more particular object to provide a process of and apparatus for cheaply making high voltage insulators.

85 Another specific object is the provision of a process of and apparatus for cheaply manufacturing insulators of the high voltage type which have none of the disadvantages above pointed out.

90 For a full understanding of the invention the principle of operation upon which it is based, and the advantages derived from it, reference is made to the accompanying drawings in which—

95 Figs. 1-4 inclusive are cross-sections of different forms of insulators made according to the invention;

Fig. 5 is a cross-sectional view of an apparatus generally adapted to carry out the object of the invention;

Fig. 6 is an end view of a part;

Figs. 7, 8 and 9 are cross-sections taken 100

on lines 7—7, 8—8 and 9—9 respectively;

Fig. 10 is a fragmentary cross-section of a modification of the arrangement shown in Fig. 5 for producing the type of insulators shown in Figs. 1—4;

Fig. 11 is an end view thereof;

Fig. 12 is a view similar to Fig. 10 showing a different relative position of the parts; and

10 Fig. 13 is a view similar to Fig. 10 of another modification.

Fig. 1 shows a typical form of an insulator as produced by the invention.

This form of insulator which has an over-all length of approximately 30 inches and is considered as safe for a line voltage of 88,000 volts under out-door conditions is operatively the equivalent of a string of six standard units of the suspension type of insulator. The only hardware employed are caps 10 and 11 secured to the ends of the tubular insulating body 12 by means of a cement bond 13. The upper end of the body 12 is closed. Between the caps and the ends 25 of the body 12 are preferably interposed gaskets or washers 14 of relatively soft material, as for instance cork, and the caps are held against the body 12 under pressure while the cement bond is applied and also 30 during the setting thereof.

The insulator shown in Fig. 2 has about the same length and voltage rating as that shown in Fig. 8 but is equipped with hardware 15 suitable for use as a post-type insulator. The tubular body 16 has a gradually increasing thickness toward the bottom in order to obtain greater bending strength as such an insulator would require.

Fig. 3 shows a post-type insulator consisting of two parts 17 and 18 interconnected by metal flanges 19 and 20 and carrying at the free ends metal caps 21 and 22 respectively for the usual purposes. The wall of the part 18 is thicker than that of the part 17 in order to obtain the necessary bending strength with a minimum of material.

Fig. 4 shows an insulator designed to replace the usual pin-type insulator in common use. The tubular body 24 carries at its lower end a flange 25 by which it can be bolted to the cross-arm 26 of a mast and the top is shaped to provide a groove 27 for receiving the line wire and a peripheral groove 28 to receive the tie-wire 29.

55 In the foregoing reference has been made to several forms of insulators which while operatively equivalent to corresponding forms of insulators now in use, have none of the disadvantages hereinbefore pointed out.

60 The forms disclosed in Figs. 1, 2 and 4 have only a single piece of porcelain or like insulating material which is electrically stressed longitudinally instead of radially whereby the unit stress is reduced to a low percentage of the values commonly dealt

with in the past and at the present time. Owing to its shape and also due to the low unit of electric stress on the porcelain the insulator will not be susceptible of failure caused by deterioration and may have a practically 70 infinite length of life. As the entire length of the insulator from end to end is of insulating material, the distortion of the field of electrostatic stress is very slight, which of course means a substantially uniform distribution of stress throughout its length. Since there are no intermediate points of hardware and therefore no bases for intermediate arcs a power arc that could be produced must necessarily extend between the 80 hardware members at the opposite ends. Such an arc is inherently forced outwardly from the cold surface of the porcelain to a greater extent than the individual arcs between points intermediate the ends, whereby 85 the danger of rupture or shattering by heat is correspondingly reduced and the liability of breakdown decreased.

It is also apparent that the use of only two pieces of hardware involves a correspondingly low cost inasmuch as the labor of cementing incident to the application of such hardware is reduced to a definite minimum.

In the following will now be described 95 the process by which the cost of making the insulators proper is also reduced to a relatively small amount as compared with the prior art referred to. The principle of operation on which the invention is based is 100 broadly disclosed in Fig. 5, which represents a standard pug-mill comprising the tubes 30 and 31 containing the screw conveyors 32 and 33 centered by spiders 32^a and 33^a, respectively and well known mechanism for 105 operating the conveyors. To the tube 31 is attached a tube or barrel 34 at the free end of which is secured a core 35 which is spaced from the walls of the barrels to define an annular passage. I preferably center the core 110 35 by means of a spider frame 36 in which the stem 37 of the core is rigidly secured. The barrel 34 is surrounded by a tubular mold 38 having a sliding fit thereon. The mold, whichever way it may be made, must be of porous material or have in general 115 a relatively large absorptive capacity. The mold is slipped over the barrel 34 and so positioned that its outer end is flush with the end of the core, as approximately indicated in dotted lines as Fig. 1. In practice plastic clay is fed into the mill and forced by the screw conveyors over the conical portion of the core into intimate contact with the walls of the porous mold 38. The force 120 of the contact and the friction of the sliding fit of the mold on the barrel are so correlated that the mold moves under the driving force of the clay maintaining the material under a definite pressure or density. The

clay thus extrudes beyond the core and is carried away in the form of a hollow cylinder. The degree of plasticity and the character of the mold are such that the cylindrical body formed remains in the position given to it by the core.

In this way it is possible to produce tubes of much thinner walls than by the usual process inasmuch as the thin wall is uniformly supported by the mold. The mold, which may be dry plaster, rapidly absorbs the water from the clay thereby giving it more rigidity and at the same time releasing the bond between the two, so that the tubes may be safely removed longitudinally, leaving the mold intact for the next operation after the same has been properly dried.

The essential feature of the arrangement for carrying out the process is the porous absorbent mold. While the clay as fed to the core and the mold has such a degree of plasticity as to provide a substantially uniform consistency and uniform density, the surplus of water is squeezed out to a considerable extent as the material is forced through the gradually constricted passage between the conical portion of the core and the end portion of the barrel 34 into the annular space. The water is carried off by the mold at the rate at which it is expelled. Aside from the stiffening of the material resulting from the expulsion of the water, the permanency of the form given to the material is promoted by the intrusion of part of the material into the pores of the mold causing a considerable force of adhesion. This force of adhesion acts a sufficient length of time to allow the material to become a hard mass. When the material finally shrinks away from the mold and breaks the bond, the form is self-supporting.

Tubes such as produced by the process just described have a limited demand, but by certain modification of the plaster mold as for instance shown in Figs. 10-13, it is possible to commercially produce tubes equipped with a plurality of sheds or deep corrugations thereby materially increasing the external surface distance or the effective electrical distance between the ends as is well understood. Porcelain tubes with such an external surface find a very useful application as insulators especially for outdoor use.

In Figs. 10 and 11 the barrel 40 is attached to the pug-mill as shown in Fig. 5. The mold 49, however, is made in two or more parts, as indicated in Fig. 11, which parts are held together by a clamp 42. The mold is provided with annular grooves 43 and the end of the core may be provided with a loosely fitting plug 44 of porous absorbent material from the inner face of which extends an air duct 45 through tube 46 to the outside. The mold is preferably

closed at its free end and is provided merely with a small aperture 47 through which the air may escape and also part of the material.

The operation is as follows:

The mold 49 is slipped over the barrel 40 and moved to the position indicated in Fig. 10 and held temporarily in this position and when the pug-mill is now set in operation, the clay is forced into the spaces defined by the mold and the core and out through the opening 47. When all the air is driven out and the material thoroughly knitted in the middle of the head the mold is released and under the force of contact and impact the mold is moved away in the manner described in connection with Fig. 5. As the feeding action continues, the annular spaces are successively filled and inasmuch as the frictional contact between the mold and the barrel has a definite value, the density of the material is uniform throughout. Naturally with uniform rate of feed of the clay, the movement of the mold is not uniform but stepwise due to the variation in the spaces to be filled. The plug 44 temporarily adheres to the inside of the head as shown in Fig. 12, and the space formed between it and the end of the core is freely filled with air entering through passage tube 45 and passage 46.

Cement lock surfaces 48 and 48a consisting of protruding corrugations or diamond-shaped points are formed in the same manner as the sheds. The tube formed will extrude to the open end of the mold but is cut off subsequently next to the cement locking surface 48.

The mold with the formed material in it is set aside for a short time allowing the plaster to absorb a sufficient amount of the water from the clay to strengthen it and to release the bond between the plaster and the clay. The two halves of the mold are then separated, the hardened plastic body removed and the plug 44 withdrawn.

The clay may now be left to dry thoroughly, then trimmed to remove the thin fins at the parting lines of the split mold, the material extending from the head of the tube and the excess tube length. The body thus prepared is then dipped in the glazing bath and after a short subsequent drying period, fired to the proper degree of vitrification.

As mentioned above, I propose to close one of the ends of the tube, preferably the upper end. This I do in order to prevent internal flash-over, which would undoubtedly cause the shattering of the porcelain. When one end is closed, any flash-over that might occur, is bound to take place outside the tube where it would be innocuous or at least of relatively small effect.

It will be noted that the under sides of

the sheds formed by the grooves 43 are substantially flat. If it should be considered desirable to provide dished sheds, the mold may be equipped with split rings. Thus as indicated in Fig. 13 the mold 50 may be provided with split rings 51 of porous or absorptive material, so that the mold may be drawn away from the formed tube after the bond is broken.

10. It is understood that the increasing thickness of an insulator according to Fig. 2 is secured by increasing the outside diameter of the tube and the sheds. The inside diameter, by the nature of the process must 15 be uniform.

The process, while more generally applicable for forming tubular bodies of all descriptions, has special utility in connection with the manufacture of high-voltage insulators for the reasons previously pointed out. Insulators may be formed quickly and cheaply. Special operations are made unnecessary.

I claim:—

25. 1. A process of molding material, which consists in forcing a plastic material against the wall of a mold thereby causing the mold to move in the direction of the axis thereof.

2. A process of molding material, which 30 consists in forcing a plastic material against the inner wall of a mold thereby causing the mold to move in the direction of the axis thereof.

3. A process of molding material, which 35 consists in forcing the plastic material against the walls of a mold of absorptive material and causing the mold to move in the direction of its axis.

4. A process of molding material, which 40 consists in forcing the plastic material against the walls of a mold of absorptive material, causing the mold to move in the direction of its axis and restraining the material against flow in opposite axial direction and radially away from the mold.

5. A process of molding material, which 50 consists in forcing the plastic material against the inner walls of a tubular mold of absorptive material causing the mold to move in axial direction and restraining the material against flow in opposite axial direction and radially away from the mold.

6. A process of molding material, which 55 consists in forcing the plastic material against the inner walls of a tubular mold of absorptive material into the space between the mold and a core, causing the mold to move in the axial direction of the core and restraining the material against flow in other directions.

7. A process of molding tubular bodies, which consists in forcing the plastic material against the walls of a mold of absorptive material under conditions such as to 60 exert pressure on the mold in axial direction

and allowing the mold to move under the said pressure.

8. A process of molding tubular bodies, which consists in forcing the plastic material partly radially and partly axially 70 against the walls of a mold of absorptive material, allowing the mold to move under the pressure exerted against it by the material and holding the material, at least during a part of the travel thereof with the 75 mold, in forced contact with the latter.

9. A process of molding tubular bodies, which consists in forcing the plastic material partly radially and partly axially 80 against the walls of a mold of absorptive material into the space between the mold and a core and allowing the mold to move under the pressure exerted against it by the material.

10. In a process of making insulators, the 85 steps which consist in forming of absorptive material an axially divided tubular mold having on its inner surface circular recesses defining sheds, forcing the plastic material radially outwardly from the center 90 against the wall of the mold, causing the mold to move axially and holding the material, at least during a part of the travel thereof with the mold, in forced contact with the latter.

11. In a process of making insulators, the steps which consist in forming of absorptive material an axially divided tubular mold having on its inner surface circular recesses defining sheds, forcing the plastic 100 material outwardly from the center against the wall of the mold partly in radial and partly in axial direction and allowing the mold to move under the pressure of the material.

12. In a process of making insulators, the steps which consist in forming of absorptive material an axially divided tubular mold having on its inner surface circular recesses defining sheds, forcing the plastic material 110 outwardly from the center against the wall of the mold partly in radial and partly in axial direction, allowing the mold to move under the pressure of the material and holding the material, at least during a part of 115 the travel thereof with the mold, in forced contact with the latter.

13. In a process of making insulators, the steps which consist in forming of absorptive material an axially divided tubular mold having on its inner surface circular recesses defining sheds, forcing the plastic material outwardly from the center against the wall of the mold partly in radial and partly in axial direction into the space between the mold and a central core and allowing the mold to move under the pressure of the material.

14. In a process of making insulators, the 130 steps which consist in forming of absorp-

- tive material an axially divided tubular mold having on its inner surface circular recesses defining sheds, forcing the plastic material outwardly from the center against the wall of the mold.
- 5 22. Apparatus according to claim 20, in which the end of the core directed toward the tube tapers toward the axis of the tube and defines means for forcing the plastic material outwardly from the center against the wall of the mold.
- 10 23. Apparatus according to claim 20, in which the end of the core directed toward the tube tapers toward the axis of the tube and defines means for forcing the plastic material outwardly from the center against the wall of the mold and in which the means for mounting the core includes a stem extending from the tapering end of the core and a spider frame secured in the tube for holding the stem and the core in position.
- 15 24. Apparatus for molding insulators, comprising an axially divided tubular mold of absorptive material having circular recesses defining sheds, a core disposed in the axis of the mold, pressure means for supporting the mold for axial movement, means for feeding plastic material toward the space defined by the mold and the core, means in advance of the core for directing the material partly radially and partly axially against the walls of the mold and means for preventing flow of the material rearwardly away from the core.
- 20 25. Apparatus for molding insulators, comprising a tube, an axially divided mold of absorptive material movably mounted on the tube and normally projecting beyond one end thereof, a core projecting beyond the same end of the tube, pressure means for feeding plastic material into the tube from the other end thereof and means for directing the plastic material outwardly from the center partly radially and partly axially against the walls of the mold, the latter having circular recesses defining sheds.
- 25 26. Apparatus for molding insulators, comprising a tube, an axially divided mold of absorptive material movably mounted on the tube and normally projecting beyond one end thereof and a core projecting beyond the same end of the tube, the mold having circular recesses defining sheds and a closed outer end provided with a perforation, and means for forcing plastic material against the mold into the space between the latter and the core.
- 30 27. In testimony whereof, I affix my signature.
